UNITED STATES PATENT OFFICE.

BERNARD W. GATES, OF PLEASANTVILLE, NEW YORK.

TAPE AND PROCESS OF MAKING SAME.

1,410,745.

Specification of Letters Patent. Patented Mar. 28, 1922.

Application filed June 15, 1918. Serial No. 240,155.

To all whom it may concern:

Be it known that I, BERNARD W. GATES, a citizen of the United States, residing at Pleasantville, in the county of Westchester and State of New York, have invented certain new and useful Improvements in Tape and Processes of Making Same, of which the following is a specification.

This invention relates to improvements in tape, and in processes of making tape. Efforts to produce a commercial paper tape which should have considerably more tensile strength than an equal weight of thick paper in plain strip form, and which should permit manipulation under stress and bending where ordinary paper would quickly tear, date back many years, as such tape might be used with equal or superior results for various purposes for which cotton tape, cotton twine and paper twine have heretofore been used or proposed. The present invention I believe to be first to succeed in this; and incidentally it provides a tape having other new and useful advantages. Among these are the retention of its flat form more persistently than any other kind of easily flexible fibrous, paper, or textile tape known to me. It is a tape moreover on which printing is easily applied and well displayed; and, oppositely, for cases where it is desired to protect printing from exposure or abrasion, it provides a flexible folded tape which persistently refuses to open or spread under any normal handling, or to collapse.

The advantages mentioned adapt this tape particularly for use in rope, for the purpose of associating printed information therewith without interfering with the rope structure. It is therefore among the objects of the invention to provide a tape whose structure is firm and which affords a large surface for receiving printed information; and yet which is so condensed together, and of such flexible character and so shaped that the body of material of which it consists does not interfere appreciably with that perfect spiral laying of threads and strands, and coordination of arrangement and tension, which is essential to the manufacture of a good grade of rope. For commercial reasons it is also important that this be done by a method involving but little cost for labor and materials. The facility with which the simple tape may be reinforced by

a wire or textile thread, at its edges, adapts it particularly for other purposes, giving still greater strength to resist tearing. When used as a twine its flatness adapts it for tying bunches of asparagus and other vegetables, and for packages where it is desired that the string shall not cut into the surface.

The invention attains these objects by a continuous process in which a flat strip of paper of suitable quality is converted into the tape as the strip is drawn forward. The first step is rolling the edges thereof repeatedly upon themselves inward and backward. The strip thus narrows obliquely to a fraction of its original width, for example, to about one-fifth of it. The narrowed tape with rolled edges is then, by organized crushing while under tension, condensed into a longitudinally wrinkled state, its two edge masses being in proximity in the middle, and the whole is by pressure flattened in parallelism with what originally was the flat way of the tape. Preferably, the pressing is done gradually, and accompanied by restrictions which prevent the rolled mass from spreading. In that case the upstanding loosely rolled edge portions, which were abutting together in the middle of the tape, adjust themselves to flat shape by each pressing beyond the middle. In so doing, a fold of one of them enters a wrinkle in the other, aided by the preliminary edge crushing operation which has broken the material into wrinkles, resulting in an interlocked arrangement of creases which makes a closed seam in the middle of one side. The tape is completed by a heavy final pressing. The multiple interior folds formed by the flattening of the original rolling are thus forced toward the edges, and, being creased by the heavy pressure, remain there in the finished product, giving strength where most needed. By the restraint against edgewise spreading existing at the time of this creasing the width of the product is made absolutely uniform.

When the tape is to be reinforced with cotton thread or otherwise a thread is introduced into each first or outside fold, and in the finished tape these two threads then lie near each edge to act as a reinforcing against possible tearing of the tape. The folded material may be of waterproof nature or may be treated with a waterproof

compound. By using adhesive materials or other compounds between the folds, various degrees of rigidity or pliability may be obtained.

5 The accompanying drawings illustrate the process by which the tape of the invention is made, one kind of apparatus for making it, and one kind of tape which embodies the invention; but it is to be understood that
10 these are merely illustrative and that variations may be made within the scope of the appended claims. It is intended that the patent shall cover by suitable expression in the appended claims whatever features of
15 patentable novelty are possessed by the process or by the product disclosed.

In the drawings:

Figure 1 is a perspective view illustrating the performance of the process;

20 Figures 2-6 are cross sections, through the material illustrated in Figure 1 at various points along its course, greatly enlarged;

25 Figure 7 is a side elevation showing the apparatus;

Figure 8 represents a form of the tape including strengthening threads; or electric conductors;

30 Figure 9 is a front elevation, enlarged from Figure 1, but not to the scale of Figures 2-6, of a detail; and

Figure 10 is a side elevation through the same viewed as in Figure 7, in section.

35 The drawings show the various stages of development of the tape from a flat strip of paper of single thickness, which may, for example, be assumed to be $1\frac{3}{4}$ " wide, to a finished folded tape which may, for example, be assumed to be $\frac{1}{4}$ " wide. The tape as a
40 whole is marked 10 and the successive portions are, respectively, the part *a*, which is the raw material, a mere flat strip of paper; *b*, where the edges are being rolled inward and backward, obliquely, until the whole has
45 been narrowed to $\frac{3}{8}$ " or thereabouts; *c*, where the structure thus produced is crushed or condensed edgewise to a width which may be less than $\frac{1}{4}$ ", being, however, permitted a little expansion in the direction of thickness,
50 and the rolls acquire furrows or wrinkles extending longitudinally, and become more or less intermeshed, and are then crushed in the original direction of thickness; *d*, where condensation or gradual compression in the
55 original direction of thickness of the strip is in progress, reducing the thickness further, accompanied by lateral restraint which prevents the furrows from becoming unmeshed, and *e*, where the condensed product
60 thus held enmeshed has been by heavy pressure flattened to and creased in its final form. The final form of the tape has the general aspect shown in the latter part of Figure 1, and has the structure illustrated, with some distortion of proportions, on an

enlarged scale in cross section in Figure 6. The under surface of the tape is smooth and constitutes a face on which printing previously applied to the tape may be clearly displayed and be easily legible, or on which 70 printing may subsequently be done. The upper surface is of two folds interlocked. When the tape is made with the apparatus herein described, the line of cleavage runs in the middle with great regularity, and in 75 much of the finished product is hardly noticeable. This line, however, is the place where the tape may be opened if desired, by successively unfolding each side until the strip is spread out in its original thinness 80 and breadth; and thus any printed matter within is displayed. Notwithstanding the slant at which the edges are rolled inward, at *b*, which distorts rectilinear elements that originally extended perpendicularly across 85 the strip, the said elements are found restored to their original perpendicularity in the finished tape, as if it had been rolled in perpendicularly. Probably this restoration occurs as the rolls pass through the die. The 90 finished tape illustrated in the drawing is eight-ply in thickness, the several folds, being engaged one within another at each edge of the finished product, and the central portion of the finished product being made up 95 by the interlocking of the outer convolutions of each side, which contain somewhat more material than the inner. The interlocking structure may be constituted by a subsidiary 100 fold or crease on one of these outer convolutions overlying the edge of the other outer convolution while its main edge underlies the edge of the said other convolution. Or the main edge of one may overlie and a subsidiary crease of it underlie the main edge 105 of the other convolution. The arrangement of this may vary in different parts of the length of the tape, it being sometimes one and sometimes the other as chance may determine. And it appears that even if this 110 feature be absent, and the two outside convolutions simply lie with the edges abutting in the middle, they are so securely held in position by the arrangement and mutual engagement of elements of the general structure that they maintain their positions very satisfactorily. Reinforcing wire or textile threads, if there be any, may lie within the inmost.

115 The process by which this product is manufactured may preferably be carried out as a continuous operation by mechanism; and in that case the apparatus needed is simple. That illustrated in the drawings consists of a die, through which the tape is drawn, intervening between a guide roll and a pair of drawing and compressing rolls. To this 120 may be added, if desired, and as illustrated, a former consisting of a tapering groove closed on its "open" side by resting against 125

the final compressing roll. In the drawings, of the strip; and the latter line bends at the spool, on which the finished tape 10 is to be wound, is marked 11 and is carried by suitable spindles which are adapted to hold 5 it removably and to cause it to rotate, and which may be driven by any suitable means, not shown. To reach this spool, the raw stock is drawn from a supply roll 9, where it has the shape of a single ply paper strip, 10 over a tension rod 14 and over a guide roll 15 and through a die 16. Thence it passes through the former 21, if desired, and then between compressing rolls 17 and 18 whose action completes it, and makes it ready for 15 spooling, or for any further treatment that may be desired. The draft may be arranged by any suitable means, preferably by the seizure of the tape between compressing rolls 17, 18, which may be equipped with inter- 20 meshing gears 20, and by positively driving one or both of said rolls. The condenser and former 21 which may be arranged to operate in conjunction with one of the compressing rolls, 18, is a simple metallic bar, 25 preferably of steel, resting smoothly against the surface of the roll and having on its face which is against the roll a tapering groove 21' of suitable size and shape to receive and condense the thickness of the tape passing 30 through it, whose width has already been condensed by the circular die 16.

The operation of this apparatus is as follows. The paper strip is started through the die 16 by rolling in the corners of its 35 leading end until a point is formed small enough to be led through the die. Then steady draft of the leading end on the other side of the die causes this rolling of the edges to progress steadily along the strip. 40 As each fresh bit of the strip reaches the die, its rolling ceases and the rolled edges thereof that have just been made are crushed edgewise of the tape so that they and the bit of tape intervening between them can 45 pass through the die loosely. This breaks up the stiffness of the stock, making longitudinal wrinkles only in the rolled portions and not the portion of tape intervening between the rolled portions, depending upon 50 the relative size of the hole through the die, the quantity of paper which has to pass, and the tightness and the angle of the rolling. The latter depends upon the distance from the die back to the guide roll and the 55 width of stock and the tension. These various elements interact and may be variously adjusted according to whatever stock is used or result desired, with the aid of a little experimenting to get the correct setting if necessary. It appears that the shape of the 60 die is not necessarily circular, as dies of various oval or elliptic shapes operate successfully. On work such as that illustrated, the plane of the plate having the circular 65 die is set at an angle to the line of draft

of the strip; and the latter line bends at the die's top edge.

The die may have straight sides or may have a chamfered throat approach or a bell mouth so that the tape is led into it gradually and without rending effect. Being set at an angle as illustrated in the drawing, the bottom and curved sides of the strip ride in over the part of the smooth concave surface approaching the place of 70 smallest diameter in the die, and are laterally crushed before the top of the same part of the strip reaches the top edge of the die. This last occurs immediately afterward, and as the strip passes through and 75 is bent upward around the edge at the rear of the die the top undergoes a drag or retardation which helps introduce some wrinkles or creases extending obliquely, but in a general longitudinal direction, with their 80 openings facing laterally, and the rolled portions are somewhat crushed in the direction of the thickness of the strip. In a tape having the original width above assumed for illustration, an inch and three-fourths, 85 drawn through a die hole of one-eighth of an inch or thereabouts in diameter, the flat structure with rolled edges may be maintained down to a width of three-eighths of 90 an inch or less, following which the crushing occurs in width and in thickness at the die, the tape expanding a little both in width and thickness after passing through. If it goes then direct to the compression 95 rolls, 17, 18, their effect will be to expand 100 it a little in width as they flatten it, and to fix it by the formation of sharp creases on each edge of each of the laminated edge-rolls in the width thus determined. It is preferred, however, to pass it through the 105 intermediate condensing and forming die 21. This causes the convolutions of paper within the rolled parts to adjust themselves gradually to a flat condition by slipping on each other as the thickness is gradually 110 reduced, edgewise expansion beyond the predetermined limit being prevented by the sides of the groove, so that the tape issuing therefrom is nearly flat and has not much slack for further edgewise expansion. Be- 115 ing then immediately subjected to the heavy compression of the rolls 17, 18, it acquires a permanent set. The same forming operation makes the under side of the tape maintain or assume a flat smooth shape 120 while the convolutions adjust themselves, because the under side of the tape is tight against the cylindrical surface of the roll 18, and such slipping of outside convolutions as occurs takes place by their slipping 125 past each other on the other side of the tape where their free edges are. As the tape has already been made flexible internally by the formation of numerous sharp wrinkles, such of these as are suitably located 130

produce an interlocking effect with each other. When the available depth of penetration of one into the other has been reached the remaining slack material, which 5 must be spread out in order to be flattened, extends under or over the creases which are interlocked until it is substantially flat. In this position and lying on the roll 18 it passes immediately to the heavy compression 10 roll 17 and thus is creased and made fixed.

The edges of the tape thus formed present a calendered, tough paper surface, better able than an edge of a paper sheet to resist a tearing or rending stress; and presents not 15 only one such surface but multiple surfaces, one behind and closely reinforcing another. These both make it more difficult to start the rending of the outmost lamination, but also continue the resistance even after the 20 outmost may have been rent. Perhaps it is because of the extreme strength of the edges that the tape is found in practice to have decidedly more tensile strength than a plain strip of paper of even greater bulk, for a 25 break under tensile stress ordinarily begins with a rending of one edge. However, the intimate laminated relation of the layers to each other, with friction between them, also helps any part of the paper which may be 30 weaker to withstand a tensile strength longer than it otherwise would. To this frictional resistance the interlocking of parts resulting from the pressing together of wrinkled surfaces contributes. If it be 35 desired to increase further the strength, threads 23 of textile or other material may be fed into the rolled edges of the original flat strip as indicated in the drawing, Figure 8; and thus in the finished product will 40 lie close to each edge, giving further reinforcement.

Any suitable material may be employed for the tape. It is to be observed, however, that the success depends largely upon those 45 peculiar characteristics of paper which enable it to take and retain a crease and to be relatively stiff where not creased. Paper that is waterproof may be employed; or paper may be treated with any other kind 50 of a compound, the treatment in such case being preferably applied just before the rolling begins, as by a moistening roller 12 carrying the compound from a pan 13 and pressing against the tape while it is going over 55 the guide 15. As the paper is rolled and put through the process immediately, the added compound does not have time to change the character of the paper so as to interfere with the performance of the process. Various such adhesives may be used, 60 it being preferred to select an adhesive composition of the type which is somewhat slippery when moist.

It is preferred to mount the steel piece 21 65 by means of a spring 22 which presses it

upon the surface of the roll 17. The spring provides a safety appliance in case of need because it can yield if an incompressible bunch occurs in the tape and also makes sure that under ordinary circumstances the face 70 of this steel piece is close against the face of the roll. The groove therein is slightly rounded and tapered, diminishing in depth from beginning to end, as seen in Figure 10 and adapted in dimensions to the material 75 that is being handled, with the idea of crowding the two abutting outer convolutions into and past each other; and it ends close enough to the place where the tape is seized between rolls 17 and 18 so that the latter catch the 80 tape with its parts thus arranged.

If it be desired to fold one edge of the paper more than the other this may be accomplished by suitably arranging the angle at which the paper is guided to the die, so 85 that either side is rolled more times than the other. The range of variation of the setting of the angle, and of the size and shape of the hole through the die, and of the distances between rolls is considerable. Indeed 90 variations of adjustment may be made in many respects, within a rather wide range; and the particular adjustment which is best in any particular case depends largely on the material in hand, or the result desired. 95

When an adhesive gum is used, whether by moistening a previously gummed surface, or by applying liquid gum, the paper need be treated on one side only, and the rolling of the edges is toward that treated side, so that 100 the folds ultimately produced enclose and fully cover the gum. This leaves a cemented interior and an exterior which is smoothly finished with whatever qualities may have been given to the paper in advance such as 105 calendering, printing, color, etc. Because of this concealment feature, any addition or treatment, such as for giving strength, or thickness, or other qualities, may be carried on that side and will be out of sight in the 110 finished product. For example, a coarse mesh textile fabric, or a waterproofing or insulating compound, or a compound for other purpose may be spread on the side of the paper which is to be turned in; and in case two wire threads are run into the rolls they will be securely separated and may be thus insulated from each other, and the tape can then serve as a two wire electrical conductor. Such threads, either textile or wire, 120 coming from supply rolls or other suitable source can be guided into the cylindrical holes made by the rolling edges *b*, the open ends of which are clearly seen in Figure 1. In the immediately following stage these 125 threads lie each within one of the edge coils of paper marked *b*, as seen in Figures 2 and 3; and in the finished product one thread lies near each edge, as indicated in Figure 8. In such a case each is separated 130

from the other and from the outside by several layers of the paper and by an equal number of layers of the insulating compound, if any, provided on the surface of the paper, in case the paper itself is not an insulator. The rigidity of the structure as a whole maintains these wires thus separated from each other; but even if the tape be twisted or crushed so as to lose its shape, the multiple intervening layers keep the wires safely separated.

Ordinarily the rolls 17, 18 may be of steel or the like hard material; but if threads or wires are to be inserted it is better to use some kind of roll having a surface that can yield under intense pressure, such as felt or rubber, because with steel the wire or thread may cut the paper when the whole is compressed between unyielding surfaces. For some kinds of work these rolls may be omitted entirely, and the rope as it issues from the die 16 may be considered the finished product. This has the advantage that the strip can be run at higher speed. The product thus made has the characteristic form, the bottom being flat and smooth, and the rolled masses at each edge of the top compressed into flat folds; but it is not as perfectly creased and does not retain its form as perfectly nor as permanently as when the restrictive former 21 and the creasing rolls 17, 18, are used. The pressure which does the work, when they are omitted, is the compression of the edge rolls between the middle under portion of the strip, and the upper rear corner of the tilted die. The tension under which the strip is held, coupled with the sharp bend of the thick mass around that corner combine to make considerable compression on the top masses coupled with a smooth flattening of the bottom as the latter goes around the corner on those cushion-like masses above it.

I claim as my invention:

1. A tape, comprising a strip of paper or the like having each edge repeatedly folded on itself and with a fold of one edge thus made intermeshed with a fold of the other edge.

2. A tape, comprising a strip of paper or the like having each edge repeatedly folded on itself, all of the folding being toward the same side of the strip; both sides of the tape being flat, the surface on one side consisting of said folded edges separated by a crevice, and the surface on the other being continuous.

3. A tape, comprising a pair of flattened rolls of paper or the like lying side by side, and integrally connected together, one at each edge of the tape.

4. A tape, comprising a strip of paper or the like, formed into two rolls extending longitudinally of the strip, retaining their integral connection, flattened into abutting

relation to each other, and combined with two threads, one of which is encased in each roll whereby the threads are protected from external and from mutual contact.

5. A tape, comprising a strip of paper or the like, gummed on one side only and having its edges repeatedly rolled on themselves toward the gummed side, and flattened, with the said rolls enclosing, covering and held by said gum.

6. A process of making tape comprising the rolling of the edges of a strip of paper or the like obliquely, until the rolls thus made are near together; crushing edgewise into a form in which the rolls contact together; crushing in the direction of the thickness of the strip, forming intermeshing wrinkles in the two rolls; and then compressing in the said direction of thickness.

7. A process of making tape comprising the rolling of the edges of a strip of paper or the like obliquely, until the rolls thus made are near together; and then compressing the said rolls and strip in the direction of the thickness of the strip into a flat sided shape with creased edges.

8. A process of making tape comprising the rolling of the edges of a strip of paper or the like obliquely, until the rolls thus made are near together; forming longitudinal intermeshing wrinkles in the rolls; and compressing the rolls in the direction of thickness of the strip under restraint uniformly limiting expansion in the direction of width of the strip.

9. A process of making tape comprising the rolling of the edges of a strip of paper or the like obliquely, until the rolls are near together; and then compressing the whole in the direction of the thickness of the strip to approximate flatness and afterward creasing the flat folds made by the compressing.

10. A process of making tape comprising the curling of the edges of a strip of flat paper or the like, and drawing the curled strip through a relatively small opening; bending the same around the further edge of the opening; and compressing flat the wrinkled mass thus produced.

11. A process of making tape comprising the curling of the edges of a strip of flat paper or the like, and drawing the curled strip through a relatively small opening; and bending the same around the further edge of the opening under tension, whereby the curled portions are compressed between the uncurled part and the edge of the opening.

12. A process of making tape comprising the curling of the edges of a strip of flat paper or the like, thereby forming a somewhat condensed mass of the strip with interior spaces; and then crumpling the mass by compression applied in the direction of the thickness of the strip, meanwhile limit-

ing expansion of the mass in the direction of width of the strip.

13. A process of making tape comprising the drawing of a strip of flat paper or the like through an opening considerably smaller than the width of the strip and mean-
while holding spread under tension that part of the tape which is close in advance of the opening, whereby buckling of the middle
10 part of the tape is prevented and the dimin-
ution to the width of the opening occurs by curling of the edges of the strip; fol-
lowed by compressing the curled portions in the direction of the thickness of the strip.
- 15 14. A process of making tape comprising the curling of the edges of a strip of flat paper or the like obliquely, until the strip as a whole becomes a mass having a small fraction of its original width and having
20 multiple thickness with internal spaces; crushing this mass in the original direction

of the thickness of the strip while limiting its expansion in the direction of width, pro-
ducing a longitudinally wrinkled state of the two curled edge masses in proximity in 25 the middle; and then by relatively severe compression in the said direction of thick-
ness, accompanied by restriction of expand-
sion in the direction of width, flattening the mass into approximate solidity thereby pro-
ducing interlocking of the two edge masses. 30

15. A tape, comprising a strip of paper or the like with each edge formed into a roll which alone constitutes the whole of one edge of the tape, the mass as a whole being 35 compressed together in all directions except the longitudinal, till its exterior is smooth and of a uniform width and thickness which the tape tends permanently to retain.

Signed at Pleasantville, this tenth day of 40
June, 1918.

BERNARD W. GATES.
